UNITED STATES PATENT OFFICE.

FRANK NÉMETH, OF ST. LOUIS, MISSOURI.

FIRE-ESCAPE.

1,115,093.

Specification of Letters Patent. Patented Oct. 27, 1914.

Application filed June 6, 1914. Serial No. 843,521.

To all whom it may concern:

Be it known that I, FRANK NÉMETH, a citizen of the United States, residing at St. Louis, State of Missouri, have invented certain new and useful Improvements in Fire-Escapes, of which the following is a full, clear, and exact description, reference being had to the accompanying drawings, forming a part hereof.

10 My invention has relation to improvements in fire-escapes; and it consists in the novel features of construction more fully set forth in the specification and pointed out in the claim.

15 In the drawings, Figure 1 is an elevation of a building showing my invention applied thereto; Fig. 2 is a vertical section (enlarged) on the line 2--2 of Fig. 1, the wall of the building and appurtenances thereto 20 being broken at different points; Fig. 3 is a vertical transverse section through the cage or elevator and building wall on the line 3--3 of Fig. 1; Fig. 4 is a horizontal sectional detail on the line 4--4 of Fig. 1; and 25 Fig. 5 is a plan of a portion of the floor of the cage or car showing the trap door in said floor.

The present invention is specially directed to fire-escapes which assume the form of 30 traveling cages, cars or elevators disposed on the outside of a building, the objects here sought being to provide a cage or car which will be fire-proof; one which is provided with means of ingress from a burning building, and with means affording ready escape 35 from the car.

A further object is to provide means for 40 protecting the car from the elements when not in actual service; to provide a car which is under perfect control of the operator; one protecting its occupants against the 45 inrush of flames from a burning building; and one possessing further and other advantages better apparent from a detailed 50 description of the invention, which is as follows:

Referring to the drawings, B, represents 55 an ordinary building provided with windows W at different floors, the wall of the building being capped or surmounted with an overhanging ledge or cornice L as shown. Adapted to travel vertically along the wall of the building, and of a length sufficient to span two or more windows horizontally, 60 is a cage or car C having rear and end walls, there being no front wall, but in lieu of

such front wall there is an abbreviated wall or balustrade h to afford protection to the passengers against accidental falling out of the car, but being sufficiently low to permit the occupants to step over the same and make a quick escape once the car is lowered to the ground. The rear and side walls of the car and the roof are lined with asbestos a, the rear wall being provided with openings O positioned to come opposite the windows W as the car passes in front of the windows, the car being equipped with asbestos roller curtains D which may be drawn across the openings O to protect the occupants of the car from the flames issuing through the windows at different floors.

The car is suspended from cables 1, fastened at each end, said cables passing over sheaves 2 at the top of the building, the sheaves being protected by casings 3 through which the cables are free to play, the sheave being mounted in the lower forked end of a hanger or suspension bolt 4. The opposite ends of the cables carry counterweights 5 properly guided in a vertical chute or conduit 6 formed by the side structural members or Z-bars 7, 7, and division wall 8; a second adjacent conduit 6' being formed on the opposite side of the wall 8. In this second 80 and outer conduit 6' are adapted to travel the anti-friction rollers 9, 9, mounted on the upper and lower brackets or tongues 10 secured to the car, the tongues 10 being free to traverse the vertical slot s formed between 85 the adjacent edges of the outer legs of the Z-bars 7 (Fig. 4). The Z's are secured to the building in any way known to the art, or they may enter into the construction of the building when the latter is first erected. 90 The opposite ends of the car are provided with angle brackets 11, the outer legs of the brackets forming tongues traversing the vertical slot s' of a conduit or tube 12 secured to the building wall by braces 13 or 100 otherwise, the said bracket-legs having secured thereto the hoisting cables 14, said cables passing over rollers 15 mounted in the lower forked ends of the hangers or suspension bolts 16, the fixed or anchored ends of the bolts 4, 16, being protected by a cover plate or cap 17. The rollers 15 are positioned at the upper end of the conduit 12 and are protected from the elements by a casing 3', the cable 14 after passing over 110 the roller descending through the conduit 12 and emerging below the ground floor of

the building, where it descends and is caused to wind over a winding roller or drum 18. The shaft 19 of the drum (supported in any way known to the art) terminates at one 5 end in a bevel pinion 20 which meshes with a corresponding pinion 21 at the adjacent end of a drive-shaft 22, the latter being driven in either direction by an electric or other form or motor M.

- 10 The floor of the car is provided with a hinged trap door 23 adjacent to which is mounted a hand-operated windlass 24, the cable 25 of which is used for raising and lowering boxes or equivalent receptacles R, 15 for the purposes of lowering an occupant of the car if necessary, or for lowering such box to obtain tools or other paraphernalia to be lifted into the car, without the necessity of lowering the car itself. The edge 20 of the door 23 has a recess or notch *n* cut therefrom to allow the cable 25 to pass through, the door being lifted automatically by the ascending bucket R as quite obvious from the drawings.
- 25 E, represents a fire engine and H, a line of hose run up to the car.

The cables 14 wind over their respective drums 18, so as to wind on or unwind therefrom at the same time, the drums always rotating simultaneously in opposite directions.

30 When not in service, the car C is lifted under the ledge L where it is protected from the elements. In case of fire, the car is lowered until it comes opposite a series of 35 windows through which access may be had into the car, and, as a precaution the asbestos curtains D are drawn so as to prevent flames shooting into the car as it passes in front of windows from which flame is issuing.

40 When the car is finally lowered, the occupants can step over the fence or balustrade *h* and make their escape. The car may then be again raised to take on more pas-

sengers. Should it be desirable to secure tools of any description after a car is once 45 raised, an operator or occupant in the car may quickly lower the box or bucket R to the ground, and after the tools have been deposited therein, the receptacle R may be quickly raised, when the tools may be put 50 to their legitimate use. As for example an ax may be raised to permit chopping away of windows, and the like.

With my present escape, a burning building may be emptied in a minimum space of 55 time.

Having described my invention, I claim:—

In combination with a building wall, vertically disposed pairs of contiguous conduits located along one of the walls of the building, a car or cage, a sheave at the upper end of one of the conduits of each pair, a counter or balance weight traversing said conduit, a cable leading from the car over each sheave and secured to the weight, a vertical slot 60 being formed in the wall of the adjacent conduit of each pair, tongues leading from the car through said slots, rollers on the tongues traversing said slotted conduit, hoisting cables for the car, rollers over 65 which said cables pass, a vertically slotted conduit contiguous to each side of the car for the housing of the hoisting cable, a tongue traversing said slot and secured to one end of the cable, a drum, and means for 70 causing the opposite end of the cable to pass over the drum, and wind on, and unwind 75 therefrom, whereby the car is raised or lowered.

In testimony whereof I affix my signature, 80 in presence of two witnesses.

FRANK NÉMETH.
